UNITED STATES PATENT OFFICE

GEORGE W. WATTS, OF WHITING, INDIANA, ASSIGNOR TO STANDARD OIL COMPANY, OF WHITING, INDIANA, A CORPORATION OF INDIANA

STILL CONSTRUCTION

Application filed August 26, 1929. Serial No. 338,360.

This invention relates to certain new and useful improvements in the construction of stills employed in processes concerned with the distillation, or conversion of hydrocarbon oils. The invention is particularly adapted to be used in those hydrocarbon oil processes wherein the oil being treated is first passed through a heating means and then is discharged into a plurality of chambers or stills wherein it is maintained at an elevated temperature for a predetermined length of time.

This invention will be fully understood from the following description illustrated in the accompanying drawings, in which:

Figure 1 is an elevational view of a pair of stills embodying the improvements of the present invention;

Fig. 2 is a horizontal cross sectional view taken on line 2 of Fig. 1;

Fig. 3 is a similar view taken on line 3 of Fig. 1.

Referring more particularly to the drawings, the numerals 5 and 6 each designate one of a pair of elongated closed receptacles or stills used with apparatus employed for the distillation of hydrocarbon oils. The stills 5 and 6 operate as a unit, and are connected together at their upper portions by means of two separate conduits designated as a whole at 7 and 8. It is to be noted that in the construction shown the conduit 8 is spaced above the conduit 7. In the ordinary type of operation of oil distillation processes the lower conduit 7 functions to transfer liquid from one still to the other, while the upper conduit 8 is employed for a similar transfer of vapors.

Each of the conduits 7 and 8 embodies an improved type of structure which obviates the possibility of the conduits becoming unnecessarily strained or broken owing to a differential vertical expansion of the two stills 5 and 6. Also, this structure is designed to permit the conduits 7 and 8 to expand horizontally without incurring any liability of their being unduly strained or broken. Each of the conduits 7 and 8 are constructed as follows:

The stills 5 and 6 are each provided with short lengths of metal tubing or pipe 9 the

outer ends of which are provided with flanged couplers 10. These lengths of tubing 9 are firmly secured to the stills in any suitable manner, such as by welding, and project from the stills in a line substantially perpendicular to the plane occupied by the two stills. To each of the flanged couplers 10 is connected a flanged coupler 11 secured to a second length of tubing 12. The tubing 12 constitutes a continuation of the tubing 9 and forms an outstanding leg projecting from the side of the still. The flanged couplers 10 and 11 are connected by bolts and may have a suitable packing interposed between them, or they may have a ground fit. The outer ends of the lengths of the tubing 12 are each connected to a right-angled elbow fitting 13. Each pair of the elbows 13 are connected together by a length of tubing 14. Thus a pair of separate conduits 7 and 8 are provided each of which communicates with the interior of the stills 5 and 6. The elbows 13 may be provided with clean-out plugs 14'. The lengths of tubing 12 and 14 may be welded to, or rolled into the elbows 13 and the flanged couplers 10 and 11 may be welded to the lengths of tubing 9 and 12.

The stills 5 and 6 are mounted upon an improved type of supporting means. This supporting means is connected to the stills 5 and 6 at their lower portions and comprises the following structure.

The side wall of the lower portion of the still 6 is provided with a plurality of brackets 16, each of which is adapted to rest upon a suitable lug 17 mounted on the upper side of a frame member 18. This frame member 18 is of rectangular form and is supported upon a suitable foundation 19 formed of concrete or the like. The foundation 19 is provided with an opening or well 20' which receives the lower end of the still 6.

The still 5 is supported so that it may be rocked or pivoted, upon its supporting means, a predetermined distance away from, or toward, the still 6. To provide for this pivotal movement, the following structure is employed.

A pair of brackets 20 are mounted upon opposite sides of the lower portion of the still

5 and are positioned in a plane substantially perpendicular to the plane occupied by the two stills. The lower ends of the brackets 20 are rounded, as shown by Fig. 1. Each of 5 these rounded bracket ends fits into a semi-circular groove or bearing formed in the upper faces of a pair of lugs or blocks 21, each of which blocks is positioned directly under one of the brackets 20. The blocks 21 10 are mounted upon a frame 22. This frame 22 is similar to the frame 18 and is mounted upon the foundation 19. The lower end of the still 5 projects below the frame 22 and into an opening or well 23 formed in the 15 foundation 19. This opening is larger than the outside diameter of the still 5 so that the latter will be free to rock or pivot on the brackets 20 to the extent desired.

To prevent the still 5 from pivoting further than is desired, a second pair of brackets 24 is mounted on the lower portion of the still. These brackets 24 are mounted opposite each other and are positioned substantially in a line which passes centrally through both 25 of the stills. A lug or block 25 is positioned below each of the brackets 24. These lugs are mounted on the frame 22 and are spaced a predetermined distance below the brackets 24, so that the still 5 will be free to rock or 30 pivot a given distance toward, or away from, the adjacent still 6 which remains substantially stationary.

Each of the stills is provided with a draw-off line 26. One of the stills is provided with 35 a conduit through which it receives the freshly heated oil, while the other still is provided with an outlet for the vapors. In the present embodiment the hot oil inlet is on the still 5, as shown at 27, and the vapor outlet is on 40 the still 6, as shown at 28.

The operation is as follows: The heated oil is supplied to the still 5 through the conduit 27. When the level of the oil reaches the conduit 7 the oil will flow into the still 6. The 45 vapors, which separate from the liquids, accumulate in the upper portion of the stills, and are drawn off through the line 28, the vapors in the still 5 passing through the conduit 8 and into the still 6. The liquid remaining in the stills is continuously or periodically withdrawn through either or both of the lines 26, as desired.

During the operation of the process the 55 temperature of the oil and vapors in the still varies. This variation of temperature causes a differential vertical expansion between the stills. This differential expansion will cause a torsional force to be exerted on the outstanding legs of the conduits 7 and 8. These 60 outstanding legs, as has been already described, are formed by the lengths of tubing 9 and 12. Since the length of tubing 12 is shown as the longer of the two, it will be twisted or distorted by this torsional force 65 to a greater extent than the shorter lengths

of tubing 9. The length of the outstanding legs should be such that they will not be twisted or distorted beyond the limits of safety. In the ordinary use of these stills, the differential vertical expansion between 70 the two stills will not exceed one inch.

When the hot oil and vapors begin to pass through the connecting lengths of tubing 14, they will be heated and thereby expand in a horizontal direction. While this expansion 75 will vary, according to the length of the tubing 14, in the ordinary type of structure this expansion will amount to between three-eighths and three-fourths of an inch. When the lengths of the tubing 14 expand, the pivotally mounted still 5 will be rocked in a direction away from the stationary still 6. This movement of the still 5 will produce a torque in the outstanding legs of the conduits 80 7 and 8 which, however, will not stress these members beyond their elastic limits. When the operation of the process is discontinued, the lengths of tubing 12 will contract, causing the still 5 to rock back toward the still 6. Also, the stills 5 and 6 will be cooled off and 85 will eventually reach substantially the same temperature. When this occurs, i. e., the contraction of the lengths 12 and the assumption of the same temperature by the stills 5 and 6, the outstanding legs will not be substantially stressed. 90

In one specific embodiment of the present invention the following structure was employed. The stills were seven feet in diameter and forty-five feet in height. The outstanding conduit legs were five feet in length while the conduit 14 connecting the legs was ten feet in length. It was found that under ordinary conditions of operation the differential vertical expansion of the stills did not 100 exceed one inch, while the horizontal expansion of the connecting conduit 14 did not exceed three-eighths to one-half inch. 105

It will be understood that the length of the outstanding legs should be such that the distortion of the legs will be so distributed throughout their length that they will not be subjected to an undue amount of strain. If ground joints are used at 10, they can be 110 arranged to provide for a sufficient movement to prevent appreciable distortion of the conduits 12. 115

In the ordinary use of the stills, the brackets 24 are employed to prevent the still 5 from 120 rocking too far and consequently falling over when the conduits 7 and 8 have been disconnected.

Heretofore it has been the practice to support such stills at their upper ends. Such 125 practice necessitates the employment of a high superstructure or framework upon which the stills are mounted. It will be seen that with the present invention such cumbersome and expensive structure is unnecessary 130

as the stills are supported at their lower ends on a simple foundation.

The foregoing detailed description has been given for clearness of understanding only, and no unnecessary limitations should be construed therefrom, but the appended claims should be construed as broadly as permissible, in view of the prior art.

I claim :

10 1. In apparatus for the heat treatment of hydrocarbon oils, a plurality of vertically disposed stills, a conduit connecting two of said stills at a point above the medial point thereof, and means for supporting one of said connected stills at a point below the medial portion thereof, said supporting means being adapted to permit the said still supported thereby to move away from or toward the other still upon the expansion or contraction 75 of said connecting conduit.

15 2. In apparatus for the heat treatment of hydrocarbon oils, a plurality of vertically disposed stills, a conduit connecting said stills at a point above the lower ends thereof, and means for pivotally supporting one of said stills, said pivoted supporting means being adapted to permit said still to rock toward, or away from, another of the stills upon the contraction or expansion of said 80 conduit.

25 3. In apparatus for the heat treatment of hydrocarbon oils, a pair of vertically disposed stills, a conduit connecting said stills at a point above the lower ends thereof, and means for pivotally supporting one of said stills at a point substantially remote from and below said conduit, said pivotal supporting means being adapted to permit said still to rock toward, or away from, the other still upon the contraction or expansion of said 85 conduit.

40 4. In apparatus for the heat treatment of hydrocarbon oils, a pair of vertically disposed elongated closed receptacles, a conduit connecting said receptacles at the upper portions thereof, means for supporting one of said receptacles in a substantially immovable manner, and means for pivotally supporting the other receptacle at the lower portion thereof, whereby the latter receptacle is permitted to rock relative to the immovable receptacle upon the expansion or contraction of said conduit.

45 5. In apparatus for the heat treatment of hydrocarbon oils, a pair of vertically disposed elongated closed receptacles adapted to receive hot hydrocarbon oil, a conduit connecting said receptacles at the upper portions thereof, means for supporting one of said receptacles in a substantially immovable manner, and means for pivotally supporting the other receptacle, said means comprising, a bracket mounted on the lower portion of the latter receptacle, and a bearing member for 90 said bracket.

6. In apparatus for the heat treatment of hydrocarbon oils, a pair of stills, a conduit connecting said stills comprising, a pair of outstanding members one of which protrudes from one of said stills and the other of which protrudes from the other still, and a member interconnecting the outer ends of each of said outstanding members, and means for supporting said stills, said supporting means being adapted to permit at least one of said 70 stills to move toward or away from the other still upon the expansion or contraction of said conduit.

7. In apparatus for the heat treatment of hydrocarbon oils, a pair of elongated stills, a conduit connecting said stills at a point adjacent their upper ends comprising, a pair of outstanding members one of which protrudes from one of said stills and the other of which protrudes from the other still, and a member interconnecting the outer ends of each of said outstanding members, means for supporting one of said stills in a substantially immovable manner, and means for pivotally supporting the other still at a point adjacent 90 the lower end thereof, whereby the latter is permitted to rock relative to the immovable supported still upon the expansion or contraction of said conduit.

8. In apparatus for the heat treatment of hydrocarbon oils, a pair of vertically disposed elongated closed receptacles adapted to receive hot hydrocarbon oil, a conduit connecting said receptacles, said conduit comprising, a pair of outstanding members one of which protrudes from one of said receptacles and the other of which protrudes from the other receptacle, said outstanding members being connected to the said receptacles at a point adjacent one end thereof, each of said outstanding members being substantially perpendicular to the plane occupied by the pair of said receptacles, and a member interconnecting the outer ends of each of said outstanding members, means for pivotally supporting one of said receptacles at a point adjacent the other end thereof, whereby the receptacle so supported is permitted to move toward or away from the other receptacle upon the expansion or contraction of the inter-connecting member of said conduit, thereby placing the outstanding members of the connecting conduit in torsion.

9. In apparatus for the heat treatment of hydrocarbon oils, a plurality of vertically disposed elongated closed receptacles adapted to receive hot hydrocarbon oil, a conduit connecting said stills comprising, a pair of outstanding members one of which protrudes from one of said receptacles and the other of which protrudes from the other receptacle, each of said outstanding members being substantially perpendicular to the plane occupied by the pair of said receptacles, and a conduit member interconnecting the 120 125 130

- outer ends of each of said outstanding members, and means for pivotally supporting one of said receptacles at a point removed from the point of connection of said conduit, said pivotal supporting means being adapted to permit said receptacle to move toward, or away from, the other receptacle upon the contraction or expansion of the interconnecting member of said conduit.
10. In apparatus for the heat treatment of hydrocarbon oils, a plurality of vertically disposed elongated closed receptacles adapted to receive hot hydrocarbon oil, a conduit connecting said stills at the upper portions thereof comprising, a pair of outstanding members one of which protrudes from one of said receptacles and the other of which protrudes from the other receptacle, each of said outstanding members being substantially perpendicular to the plane occupied by the pair of said receptacles, and a conduit member interconnecting the outer ends of each of said outstanding members and disposed at substantially right angles to each of the same, and means for pivotally supporting one of said receptacles at a point below its medial portion, said pivotal supporting means being adapted to permit said receptacle to move toward, or away from, the other receptacle upon the contraction or expansion of the interconnecting member of said conduit, whereby the said outstanding members of said conduits will be placed in torsion.
11. In apparatus for the heat treatment of hydrocarbon oils, a pair of vertical still chambers, means for supporting said stills, one of said still chambers being pivotally supported by said support means, and a conduit connecting said stills, said conduit being connected to the pivotally mounted still at a point removed from its point of pivotal mounting, said conduit comprising a pair of laterally extending members one of which is secured to one of said stills and the other of which is secured to the other still, and a member inter-connecting the outer ends of each of said extending members, the length of said extending members being such that the torque exerted upon them upon expansion or contraction of the inter-connecting member and consequent pivoting of said still chamber will not exceed the elastic limit of the material from which said extending members are made.
